Primary Examiner — Sandra S Snapp*Assistant Examiner* — Ieisha N Price(74) *Attorney, Agent, or Firm* — Nixon & Vanderhye P.C.(57) **CLAIM**

The ornamental design for a fastening device for antenna, as shown and described.

DESCRIPTION

FIG. 1 is a top front perspective view of a fastening device for antenna according to the present invention;

FIG. 2 is a rear elevation view thereof;

FIG. 3 is a front elevation view thereof;

FIG. 4 is a right side view thereof;

FIG. 5 is a left side view thereof;

FIG. 6 is a top plan view thereof; and,

FIG. 7 is a bottom plan view thereof.
